CUSHIONING MECHANISM

Hubert L. Spence, East Cleveland, and Donald Willison, Maple Heights, Ohio, assignors to National Malleable and Steel Castings Company, Cleveland, Ohio, a corporation of Ohio

Original application May 9, 1947, Serial No. 747,014, now Patent No. 2,644,684, dated July 7, 1953. Divided and this application November 29, 1952, Serial No. 323,174

10 Claims. (Cl. 267—9)

1

This invention relates to cushioning mechanism, and more particularly to a cushioning mechanism for use on railway vehicles.

This application is a division of an application of Hubert L. Spence and Donald Willison, Serial No. 747,014, filed May 9, 1947 and issued as Patent No. 2,644,684 on July 7, 1953.

An object of our invention is to provide a cushioning mechanism in which resilient material, such as rubber, is associated with friction-generating means in a novel manner.

Another object is to provide a cushioning mechanism having rubber means for cushioning shocks as well as for actuating the associated friction-generating means.

A further object is to provide a cushioning mechanism in which a single block of rubber serves to cushion shocks and also simultaneously to actuate the associated friction members.

A more specific object is to provide a cushioning mechanism comprising a pair of friction members with rubber means therebetween adapted to cushion shocks and to urge the members laterally into engagement with associated friction surfaces.

A still further object is to provide a cushioning mechanism comprising relatively movable friction members having opposed sloping plane surfaces and a rubber block interposed between the surfaces adapted to cushion shocks applied to the mechanism and to urge the members into engagement with associated friction surfaces.

Other objects and advantages of our invention will be apparent from the following description of our invention taken in conjunction with the drawings in which:

Fig. 1 is an elevational view, partly in longitudinal vertical section of an embodiment of the invention.

Fig. 2 is a transverse vertical sectional view taken along line 2—2 of Fig. 1.

Referring to the drawings, there are illustrated a pair of similar interfitting relatively movable friction members 70 with a rubber cushion unit 71 interposed therebetween. Each member 70 comprises a wedge portion 72 having a sloping face 73 for engagement with cushion unit 71 and a horizontal wall 74 to which preferably a wear plate 75 is secured by means of a weld. Each member also is formed with a pocket por-

2

tion 76 for carrying cushion unit 71 and for receiving the cooperating wedge 72 of the other friction member. Each pocket is provided with a surface 77 on transverse wall 78 for engagement with wear plate 75 of the adjacent wedge. The sidewalls 81 of each friction member are formed with diagonally extending end surfaces 82 which oppose each other in spaced relationship and are adapted to engage during the operation of the mechanism to limit the relative movement between the friction members. Side-walls 81 also serve to prevent walls 78 from being distorted outwardly by the wedging action. Each side wall 81 preferably extends beyond wedge portion 72 of the friction member, as at 39, to assure full surface contact between the opposed diagonal surfaces 82. Each member 70 also is provided with an abutment wall 83 against which the forces and shocks to be cushioned are applied to the device. Cushion unit 71 which is interposed between wedge faces 73 comprises a block of resilient material, preferably rubber, with plates 84 vulcanized or otherwise bonded to the sides thereof. Unit 71 is precluded from sliding relative to wedge faces 73, during actuation of the mechanism, by means of shoulders 85 on each member 70, which are in engagement with plates 84. Guide ribs 86 are provided on side walls 81 adjacent wedges 72 to maintain the parts in proper position laterally of the mechanism.

Operation of the mechanism is as follows:

As a compressive force is applied to abutment walls 83 of the mechanism, members 70 will move relative to one another in a longitudinal direction. The cushion unit 71 will resist the relative movement and will simultaneously urge wear plates 75 of wedge portions 72 against friction surfaces 77 on transverse walls 78 of the opposing member. Thus the compressive force applied to the mechanism is resisted by the cushion unit which is subjected to combined compression and shear and by the ever increasing frictional forces generated between wedge portions 72 and the surfaces 77 as the friction members move relative to each other. This action will continue as the applied force increases until opposing surfaces 82 engage to limit further compression of the mechanism.

The sides and ends of the rubber blocks are undercut slightly to preserve the bond between

3

the rubber and the plates 84, and spaces 87 and 88 adjacent the block are provided to allow greater space for the flow of the rubber during compression of the mechanism.

In view of the practical impossibility of forming friction members 70 of identical dimensions, after the parts are initially assembled and placed in operation, it is contemplated that the wear plate 75 of only one of wedges 72 will be in engagement with its associated friction surface 77, and a clearance will exist between the other wear plate and its associated surface. Therefore, as relative longitudinal movement between members 70 occurs in operation, cushion unit 71 and the friction between only one of plates 75 and surface 77 will oppose such movement. As the compressive force applied to the abutments increases, the wedging action between the rubber and wedge 72 will urge the one plate 75 and surface 77 into tighter engagement. Operation of the device in this manner will continue until wear between plate 75 and the engaged surface 77 will cause frictional engagement to take place between the other plate 75 and its associated surface 77. Thereafter, the friction generated between both wear plates and their engaging friction surfaces 77 will be available to absorb and cushion shocks.

The terms and expressions which we have employed are used as terms of description and not of limitation, and we have no intention, in the use of such terms and expressions, of excluding any equivalents of the features shown and described or portions thereof, but recognize that various modifications are possible within the scope of the invention claimed.

We claim:

1. In a cushioning mechanism a pair of similar relatively movable interfitting members, each member comprising a wedge portion and a pocket portion, each of the wedge portions being received in the pocket portion of the other member, each of the pocket portions having a surface engaged by the wedge portion received in the pocket portion, and a resilient pad interposed between the wedge portions and adapted to cushion relative movement between the members and to urge the wedge portions laterally against the friction surfaces in the pocket portions.

2. In a cushioning mechanism a pair of similar relatively movable interfitting members, each member having a longitudinally extending friction surface and a wedge portion, each wedge portion being in engagement with the friction surface on the other member, and a resilient pad interposed between the wedge portions for resisting relative movement between the members and for urging the wedge portions against the friction surfaces.

3. A cushioning mechanism comprising a pair of similar relatively movable interfitting members having friction surfaces in slidable engagement with one another, said members having opposed surfaces sloped lengthwise of the mechanism, and a resilient pad interposed between said sloping surfaces adapted to cushion relative movement between said members and to urge said friction surfaces into tighter engagement.

4. In a cushioning mechanism a pair of relatively movable interfitting members, each of said members having a wedge portion and a friction wall, said wedge portion of each member being in slidable engagement with said wall of the other member, said wedge portion of each member having a face directly opposing the correspond-

4

ing face on the wedge portion of the other member, and a resilient pad interposed between and in engagement with said faces adapted to cushion relative movement between said members and to urge each wedge portion against the friction wall of the other member with increasing force.

5. A cushioning mechanism comprising a pair of members movable longitudinally relative to each other, each of said members having a longitudinally sloping surface opposing a corresponding sloping surface on the other member, each of said members having a friction surface in slidable engagement with a friction face on the other member, a resilient pad interposed between the sloping surfaces to cushion relative longitudinal movement between said members and simultaneously to urge said friction surface on one member into tighter engagement with said friction face on the other member.

6. A cushioning mechanism comprising a pair of members movable longitudinally relative to each other, each of said members having an abutment wall and a plurality of walls extending from said abutment wall, certain of said walls being in slidable engagement with complementary walls of the opposing member, another of said walls being sloped lengthwise of the mechanism and being in spaced opposed relation to the corresponding wall of the opposing member and resilient means interposed between the sloped walls of said members for opposing relative longitudinal movement between said members and simultaneously for urging said slidably engaged walls into tighter engagement.

7. A cushioning mechanism comprising a pair of members movable longitudinally relative to each other, said members having slidably engaged friction surfaces and opposed longitudinally sloping surfaces, and resilient means interposed between said sloping surfaces for directly cushioning relative longitudinal movement between said members and simultaneously for urging said friction surfaces into tighter engagement.

8. In a cushioning mechanism, a pair of relatively movable interfitting members, each member having a wedge portion and a friction wall, the wedge portion of each member being in slidable frictional engagement with the friction wall of the other member, a resilient pad interposed between the wedge portions adapted to cushion relative movement between the members, each member having abutment means for engagement with the other member to limit relative movement between the members.

9. A cushioning mechanism comprising a pair of relatively movable interfitting members, each member having a wedge portion and a pocket portion, the pocket portion in each member having a friction surface, the wedge portion of each member extending into the pocket portion of the other member and being in engagement with the friction surface therein, the wedge portion of each member being in opposed relation to the wedge portion of the other member, resilient means interposed between the opposed wedge portions, each pocket portion having guide means for maintaining the members in proper position laterally of the mechanism.

10. A cushioning mechanism comprising a pair of members movable longitudinally relative to one another, each of said members having an abutment wall and a plurality of walls extending from said abutment wall, at least one of said walls of each member having a diagonally extending end surface in spaced opposed rela-

tionship to a complementary surface on a wall of the other member, said surfaces being adapted for engagement to limit relative movement between said members, other of said walls being in 5
slidable engagement with complementary walls of the opposing member, another of said walls being sloped longitudinally of the mechanism and being in spaced opposed relationship to the corresponding wall of the other member, and resilient means interposed between the sloped 10 walls of said members for opposing relative longi-

tudinal movement between the members and for urging said slidably engaged walls into tighter engagement.
